(57) CLAIM

The ornamental design for a panty with abdominal pocket for a heating pad, as shown and described.

DESCRIPTION

FIG. 1 is a front perspective view of my new a panty with abdominal pocket for a heating pad;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even broken lines on the exterior surfaces of the panty, with a thin, continuous solid line passing through the dashes, depict stitching, which forms a part of the claimed design. The dash-dash broken lines illustrate portions of the panty that form no part of the claimed design.
